INCINERATOR

Edward C. Folsom, Cleveland, and John R. Olfs,
Toledo, Ohio, assignors to Railways Material
Corporation, Toledo, Ohio, a corporation of
Ohio

Application July 23, 1932. Serial No. 624,164.

7 Claims. (Cl. 110—18)

This invention relates to incinerators.

This invention has utility when incorporated in incinerators for facilitating assembly thereof, quick replacement of broken parts, substantial construction, and expansion take-up regardless of heat distribution therein.

Referring to the drawing:

Fig. 1 is a side elevation of an incinerator embodying the invention herein;

10 Fig. 2 is a view on the line II—II, Fig. 1;

Fig. 3 is a plan view of the incinerator of Fig. 1, parts being broken away; and

Fig. 4 is a perspective view of a corner of the incinerator showing details of assembly.

15 Castings 1 may be set in concrete base 2 and so disposed that they provide properly positioned sockets 3 for incinerator frame members 4, 5. The frame members 4 comprise angle pieces of a length to determine the height of the incinerator to be assembled. They may be cut from standard angle stock and form the corners of the completed incinerator. The sockets 3 have the side walls thereof so configured as to form seat 6 for the lower termini of the corner members 4 so that the incinerator will be kept from shifting as to its mounting.

20 Frame members 5 are also cut from standard angle stock and a member 5 is disposed adjacent each member 4 and spaced therefrom to form a way 7 therebetween.

25 Rods 8 extend horizontally through the frame members 4, 5, and have nuts 9 on each end thereof. These rods 8 connect the four corners of the incinerator and are in two sets, one at the top and one adjacent the bottom but spaced some distance above the base 2.

30 Disposed above the lower set of rods 8 and forming the lower peripheral corner of the incinerator chamber 10 are slats 11, having their termini 12 disposed in the ways 7. These termini are beveled so that each contacts the abutting pair of slats at the incinerator corners between the frame members 4, 5. These termini 12 space the members 4 from the members 5 in determining the ways 7 as well as the members 4 from each other and as in place may be clamped between the frame members 4, 5, by tightening the nuts 9 on the rods 8. The slats 11 are alike and are provided with ledges 13 integrally cast therewith. The frame as thus far assembled comprises four way providing corners with a lower inwardly extending peripheral ledge 13 maintained in assembly by the rods 8.

35 The bottom of the chamber 10 may now be assembled by placing a series of marginally

notched bars or slats 14 on the ledges 13 to extend from the ledge of one slat 11 to the ledge of the opposing slat. The notches 15 on one edge of the bars 14 are staggered as to the notches on the other edge thereby maintaining strength 60 in the bar. The bars are alike and when placed to form the chamber bottom, the notches 15 of one bar cooperate with the notches of each abutting bar to form openings through the bottom.

45 Superimposed on each slat 11 is a series of horizontally disposed relative narrow slats 16 having their termini 17 extending into ways 7. The thickness of these termini 17 is just less than the thickness of the termini 12 of the slats 11 so that there is a looseness in the assembly as to the frame members. The slats 16 are of a length less than the slats 11 so that there may be lateral shifting in the ways. This shifting is limited by lugs 18 on the slats 16 which allow 70 a certain amount of lateral shifting and expansion but prevent sufficient movement to remove the slats except by vertical shifting up out of the ways 7.

50 These slats 16 are superimposed one upon the other to desired height whereupon a second series of slats 11 is superimposed upon the uppermost slat 16. The second series of rods 8 is disposed just below the upper slats 11 and as the slats 16 are placed in the ways with the finishing or upper ledge providing slats in place, the upper set of nuts 9 may be drawn up on their respective rods to complete the side wall assembly.

55 The height of the side walls may be predetermined and the frame members 4, 5, cut accordingly. Regardless of the side wall height, the same slats may be used.

60 Perforate cover 19 may be carried by the upper ledge 13 and have handle 20 for shifting thereof. In some instances it may be desired to provide 95 means for foot raising of the cover 19. To this end one pair of opposing frame members 4, may be extended above the incinerator and provided with openings 21 therethrough to receive stub rods 22 from the cover 19 forming a hinge for 100 the cover. Stub rod 23 may be spaced from the rod 22 and also carried by the cover 19. Bar 24 extends therefrom to have hinge connection 25 with bar 26 mounted on fulcrum 27 and terminating in pedal 28 so that by depression of the pedal 28 by foot 29, the cover will swing upwardly on the hinges 22 and the hands will be free to dump refuse and trash into the chamber 10.

65 The cover can then be dropped and the refuse will be confined so that upon ignition thereof, 110

ready burning may be had as sufficient draft is produced through the openings formed by the notches 15 in the slats 11 and 16 as well as through the perforated cover 19.

5 This incinerator is readily assembled and the slats are all castings of which any one may be replaced if broken. The loose assembly of the side wall forming slats allows ample expansion from heat of the burning refuse without distortion.

10 The different temperatures in the different parts of the chamber are also cared for by the built-up construction. The casting construction provides sufficient weight to insure substantial construction which together with its fixed

15 mounting may be placed in convenient spots as along railway right-of-ways to receive refuse from trains or train centers and ignited and left to burn without attention. The side wall and bottom openings as well as those in the cover

20 are of such size that sparks and blazing embers are confined within the chamber 10.

Ash pan 30 is provided below the chamber 10 to receive the ashes therefrom.

What is claimed and it is desired to secure by 25 United States Letters Patent is:

1. An incinerator comprising a frame embodying corner members, a second set of corner members spaced therefrom, means assembling said corner members to provide ways therebetween, and a series of superimposed slats having their termini loosely disposed in said ways to form the side walls of the incinerator.

2. An incinerator comprising a frame embodying corner members, a second set of corner members spaced therefrom, means assembling said corner members to provide ways therebetween, a slat having a longitudinal flange forming a ledge having its termini in said ways, and a plurality of slats superimposed on said slat providing the ledge and having their termini in said ways to form a side wall for the incinerator.

3. An incinerator comprising a frame embodying corner members, a second set of corner members spaced therefrom, means assembling said corner members to provide ways therebetween, a slat having a longitudinal flange forming a ledge having its termini in said ways, a plurality of slats superimposed on said slat providing the ledge and having their termini in said ways to form a side wall for the incinerator, and a series of slats having their termini supported by the ledge to form a bottom for the incinerator.

4. An incinerator comprising a frame embody-

ing corner members, a second set of corner members spaced therefrom, a slat of definite thickness having its termini disposed between said corner members to determine the spacing thereof in providing a way, and a series of slats laterally superimposed thereon, said slats having their termini disposed in said way and said slats being of less thickness than the way defining slat to be loosely held in forming an incinerator side.

5. An incinerator comprising a frame embodying corner members, a member spaced inwardly from each corner member, a first series of slats having their termini disposed between said frame members in determining the spacing between the corner members, means assembling said corner members and first slats into a frame, and a second series of slats relatively thinner than the first series having their termini loosely disposed in said ways and superimposed to form the side walls of said incinerator.

6. An incinerator comprising a frame embodying a plurality of parallel angle members each forming a corner thereof, an angle member spaced inwardly from each corner member forming a way therebetween, means assembling said angle members, a lower series of slats carried by said frame with their ends in said ways and having inwardly extending longitudinal flanges forming ledges, a series of slats carried by the ledges to form a bottom for the incinerator, said last named slats having openings, an intermediate series of slats having openings and superimposed on said lower series of slats and having their ends in said ways to form side walls for the incinerator, an upper series of slats with their ends in said ways and having longitudinal flanges forming ledges and superimposed on the side wall forming slats, and a cover carried by the last named ledges.

7. An incinerator comprising corner members providing opposing ways, a lower series of slats, one thereof having their ends in each of said pair of opposing ways, means assembling said corner members and lower series of slats into a frame, said slats determining the frame assembly, and a second series of opening-providing slats super-imposed on the lower series of slats to provide walls for the incinerator, said second series of slats having their ends loosely disposed in said ways.
